UNITED STATES PATENT OFFICE.

JOHN W. MITCHELL, OF ELLSWORTH, PENNSYLVANIA, ASSIGNOR OF ONE-HALF TO
JAMES V. MITCHELL, OF ELLSWORTH, PENNSYLVANIA.

INTERNAL-COMBUSTION ENGINE.

1,169,556.

Specification of Letters Patent. Patented Jan. 25, 1916.

Application filed January 23, 1915. Serial No. 3,995.

To all whom it may concern:

Be it known that I, JOHN W. MITCHELL, a citizen of the United States, residing at Ellsworth, in the county of Washington and 5 State of Pennsylvania, have invented certain new and useful Improvements in Internal-Combustion Engines; and I do hereby declare the following to be a full, clear, and exact description of the invention, such as 10 will enable others skilled in the art to which it appertains to make and use the same.

This invention relates to internal combustion engines, and more particularly to those driven by means of an inflammable mixture 15 of vaporized gasolene or oil and air; and it consists in the novel construction and combination of the parts hereinafter fully described and claimed.

In the drawings, Figure 1 is a vertical section through an engine constructed according to this invention. Fig. 2 is a side view 20 of the engine looking at one end of its crankshaft.

Any suitable supporting frame 2 is provided, and 3 is the crankshaft which is journaled in bearings 4 on the frame, and provided with a crank 5. The power cylinder 6 is secured to the frame, and is kept cool in any approved way, and is provided 30 with a piston 7. A connecting-rod 8 is pivoted to the piston, and operates to revolve the crank 5 in the usual manner.

At the rear end of the cylinder, which is the other end from the crankshaft, a combustion chamber or space 10 is provided which is frusto conical in form, and at the smaller 35 end of this chamber an exhaust valve 12 is arranged. This valve is preferably a lift valve provided with a central stem 14, and having a spring 15 which normally holds the 40 valve on its seat.

A cam 16 is provided on the crankshaft, and this cam operates a rod 17 periodically, and opens the exhaust valve 12 by means of 45 a trip lever 18. The trip lever 18 is pivoted to a bracket 19 on the cylinder. One end of this lever is pivoted to the upper end of the rod 17 by a pin 20, and its other end is operatively connected with the stem of the exhaust valve.

The drawings show the piston at the front end of its stroke, and the exhaust valve open.

The cylinder has an inlet port 21 at its front end portion which is uncovered by the

piston as it nears the front end of its stroke, 55 and after the exhaust valve has been opened. An inlet valve 24 is arranged to slide in the inlet chamber 25, and has a projecting stem 26. A cam 27 is secured on the engine crank-shaft, and operates to slide the inlet valve 60 24 in one direction at suitable intervals. A spring 22 is provided for moving the valve in the reverse direction. The stem 26 of the valve works in a suitable stuffing-box 28, and is provided with an adjusting device 65 29 of any approved construction so that the inlet valve may be regulated to open and cut off earlier or later, as required.

The inlet pipe 30 is connected to the inlet chamber 25, and a blower or fan 31 is connected to the inlet pipe. The eye or intake of the blower is connected to a carbureter 32 of any approved construction by a pipe 33, and this pipe 33 has also an air valve 34 on one side of it so that the composition of 75 the inflammable charge may be varied. The carbureter has a supply pipe 35 for gasolene or oil, and an air supply pipe 36.

The blower or fan 31 is of any approved construction, and it is driven from the crank-shaft by any approved driving mechanism, such as a driving belt 38 which passes over a pulley 39 on the blower shaft and over a pulley 40 on the crankshaft. The blower is revolved continuously, and the inlet pipe 80 30 and the inlet chamber 25 form a reservoir for the inflammable mixture. When a prearranged low pressure is attained in this reservoir, the blower runs idly, so that the pressure in the reservoir never becomes excessive. When the exhaust valve is opened 90 the products of combustion expand through it, and the inlet port is opened so that the front end portion of the cylinder, next to the piston, is filled with inflammable mixture. As the piston moves rearwardly most 95 of the products of combustion are forced through the exhaust valve, which is then closed, and the inflammable mixture is compressed in the combustion chamber during the latter part of the rearward stroke of the piston.

The compressed inflammable mixture is ignited, by any suitable igniter 42, when the piston commences its forward stroke.

A series of engines, such as hereinbefore described, is preferably arranged with the cylinders side by side, and the crankshaft

has its cranks arranged at suitable angles so that the cylinders may exert power one after another in regular order.

The valve 34 is not ordinarily required to be opened, and all the air and hydrocarbon are ordinarily drawn through the carbureter by the fan blower, and are intimately mixed together by its arms or vanes. The inflammable mixture is forced by the fan blower 5 into the inlet pipe 30, or into the inlet manifold when several cylinders are used. The inlet pipe forms a reservoir in which the mixture is held under a substantially constant pressure, and from which the cylinder 10 is freely supplied when the inlet valve is opened. The engine piston is relieved of the work of drawing the inflammable charge into the cylinder, and the pressure in the cylinder is not reduced below that of the atmosphere during the inlet or out-stroke.

What I claim is:

1. In an internal combustion engine, a cylinder, a piston reciprocating in the cylinder, the cylinder being provided with an inlet 25 port overrun by the piston at the end of the working stroke, and a valve controlled exhaust at the other end of the cylinder, a valve casing communicating with the inlet

port, a slide valve in the valve casing controlling the cylinder inlet port, means for operating the valves from the crank-shaft, and a fan blower discharging into the valve casing.

2. In an internal combustion engine, a cylinder, a piston reciprocating in the cylinder, a crank shaft, the cylinder being provided with an inlet port overrun by the piston at the end of the working stroke, and a valve controlled exhaust port at the other end of the cylinder, a valve casing communicating with the inlet port, a hollow piston valve slidable in the valve casing open to the top of the casing and closed at the bottom and provided with a port adapted to register with the cylinder inlet port, a fan blower discharging into the upper end of the valve casing, a carbureter connected to the fan blower, and means for operating the valves from the crank shaft.

In testimony whereof I have affixed my 50 signature in the presence of two witnesses.

JOHN W. MITCHELL.
